UNITED STATES PATENT OFFICE.

JAMES H. STOCKHAM, OF DES MOINES, IOWA.

DESIGN FOR A BADGE OR SIMILAR ARTICLE.

SPECIFICATION forming part of Design No. 32,912, dated July 10, 1900.

Application filed June 2, 1900. Serial No. 18,905. Term of patent 7 years.

To all whom it may concern:

Be it known that I, JAMES H. STOCKHAM, a citizen of the United States of America, residing at Des Moines, in the county of Polk, in the State of Iowa, have invented and produced a new and original Design for a Badge or Similar Article, of which the following is a specification, reference being had to the accompanying drawings, forming a part thereof.

Figure 1 is a plan view of a badge or similar article; showing my new design; and Fig. 2 is a sectional view taken on line 2 2 of Fig. 1.

As shown in the drawings, the leading or material feature of my design consists of a stem A of a plant or shrub bearing three leaves B, C, and D, extending at an angle

from one another, the whole being surmounted by an ornamental scroll E, joined near its center to the middle leaf and having its ends extending therefrom in a graceful curve toward 28 the side leaves. The general form of the stem and leaves is that of a clover or shamrock plant.

Having thus described my invention, what I claim as new, and desire to secure by Letters 25 Patent, is—

The design for a badge or similar article, substantially as herein shown and described.

JAMES H. STOCKHAM.
